EYELASH BUFFER

Clara J. Altman, Detroit, Mich.

Application January 1, 1945, Serial No. 570,900

1 Claim. (Cl. 15—244)

1

This application relates to eyelash buffer and discloses a novel form of buffer and holder.

The buffer hereof is disclosed in the appended drawing whose

Fig. 1 is an end view of the holder of the buffer; and whose

Fig. 2 is an end view of the holder with the sponge rubber buffer therein;

Fig. 3 is a side view showing the holder, with the buffer in place;

Fig. 4 is a plan view of the holder only, with the buffer shown in dotted lines;

Fig. 5 is a diagrammatic view illustrating the use of the device.

The eyelash buffer hereof comprises a long bar 10 of sponge rubber having a square cross section so as to provide a plurality of long sharp edges 11. The holder 12 for the bar is arranged to grip the bar at its ends. The holder comprises a central rod or handle portion 14 and two transverse end portions 15, each having a central hole 16 so that in effect the end portions are in the form of rings which detachably receive the ends of the sponge rubber bar.

The buffer hereof may be held by the fingers of the user at the central handle portion and moved toward an eyelash, for example, the upper eyelash 20 as shown in Figure 5, so that one edge thereof

2

rubs against the upper eyelash from below. The buffer can thus be manipulated to wipe off excess mascara, and also to spread mascara evenly over the entire lash, and also the buffer may be used to fluff the eyelash, brushing or combing it, and thus overcome the tendency of the mascara to cause the separate hairs of the eyelash to stick together.

The buffer may also be wetted so as to be useful to wash mascara off an eyelash without disturbing the face make-up.

Now having described the buffer herein disclosed, reference should be had to the claim which follows:

15 I claim:

An eyelash buffer comprising a sponge rubber bar and a holder therefor, the bar being elongated and formed with several flat sides and a plurality of longitudinally extending sharp edges, the holder being in the form of a long base formed with transversely extending rings at its ends detachably receiving and gripping the ends of the bar, whereby only the ends of the bar are engaged by the holder, so as to leave several of said edges and said sides of the bar completely exposed and free of the holder.

CLARA J. ALTMAN.
